(57) **CLAIM**

The ornamental design for a dental floss holder, as shown and described.

DESCRIPTION

FIG. 1 is a front view of a dental floss holder, showing our new design;

FIG. 2 is a right side view thereof;

FIG. 3 is a top plan view thereof; and,

FIG. 4 is a sectional view thereof, taken along line 4-4 of FIG. 1.

In the drawings, the broken lines shown represent portions of the dental floss holder that form no part of the claimed design. The dot-dash lines represent only the boundary between the claimed portion and unclaimed portions. The rear view is omitted, because it is a mirror image of the front view. All sides not shown except for the rear view form no part of the claimed design.
